(57) **CLAIM**

An ornamental design for a marking tool for an electrical junction box, as shown and described.

DESCRIPTION

FIG. 1 is a top, front, right side perspective view of a marking tool for an electrical junction box.

FIG. 2 is a front elevation view thereof.

FIG. 3 is a back elevation view thereof.

FIG. 4 is a right side elevation view thereof.

FIG. 5 is a left side elevation view thereof.

FIG. 6 is a top plan view thereof; and,

FIG. 7 is a bottom plan view thereof.

The broken lines depict portions of the marking tool for an electrical junction box that form no part of the claimed design.
